UNITED STATES PATENT OFFICE.

ALLAN J. AITKEN, OF BUFFALO, NEW YORK, ASSIGNOR TO THE BARBER ASPHALT
PAVING COMPANY, OF PHILADELPHIA, PENNSYLVANIA, A CORPORATION OF
WEST VIRGINIA.

VALVE.

1,103,241.

Specification of Letters Patent. Patented July 14, 1914.

Application filed April 14, 1913. Serial No. 760,863.

To all whom it may concern:

Be it known that I, ALLAN J. AITKEN, of Buffalo, in the county of Erie and State of New York, have invented certain new and useful Improvements in Valves, whereof the following is a specification, reference being had to the accompanying drawings.

The invention relates more particularly to a pivoted valve, which is held by spring pressure against the valve seat.

An object of the invention is to provide a valve which is located on the inner face of a receptacle adapted to hold a fluid to be discharged, which valve is controlled by means extending above the edge of the receptacle.

A further object of the invention is to provide means for holding the valve seated, which includes yielding means for pressing the valve against its seat, and devices co-operating therewith, which insure the proper seating of the valve.

In the drawings which show by way of illustration one embodiment of the invention, Figure I, is a view from the inside of the receptacle, showing the valve in side elevation. Fig. II, is a vertical sectional view on the line II, II of Fig. I. Fig. III, is a sectional view on the line III—III of Fig. I. Fig. IV, is a plan view of the valve seat.

In the drawings the valve is shown as applied to a receptacle indicated in part at 1, said receptacle comprising side and end walls and a bottom 2. The wall of the receptacle is formed with an opening, and surrounding said opening is a valve seat plate 3, which rests on an asbestos pad 4, and is bolted to the receptacle by suitable bolts 5. This valve seat plate is formed with an opening registering with the opening of the wall of the receptacle, and a pipe 6, extending through said opening is threaded into the valve seating plate. Said valve seating plate is provided with a flat valve seat 7. A valve 8, engages said valve seat, and is adapted to close the opening therethrough. This valve 8, is formed with a lateral extension 9, which is pivoted upon a supporting stem 10. The valve seating plate is recessed as at 11, to receive the head of the valve seating stem 10. A spring 12, surrounds said stem, and at one end bears against the valve 8, while the other end of

the spring engages a washer 13, which is held from movement on the stem by suitable nuts 14. The outer end of the valve extension rests on a lug or projection 15. This projection is so disposed relative to the valve seating plate that the valve 60 rests on the projection or lug at one end, and on the valve seat at its other end. In other words, the valve at a point through which the stem extends is substantially out of contact with the valve plate, as shown in Fig. III. This allows the spring pressing upon the valve to force the valve against its seat, the lug or projection 15, serving as a fulcrum for the action of the spring. A stop 16, limits the movement of the valve 70 when in closed position. The valve is operated by a bar 17, which is pivoted at 18, to the valve, and this bar extends upwardly above the top of the receptacle 1, where it may be provided with any suitable actuating mechanism.

From the above description it will be apparent that I have provided a valve which is located within the receptacle containing the fluid, and, therefore, all parts of the valve are subjected to the action of the fluid. This is particularly desirable in connection with the control of the discharge of bituminous materials from a melting tank or the like. Where the valve is located outside of the tank, the bituminous material coming in contact with parts of the valve, cools and clogs the valve, so that it is difficult to operate the same. By locating the valve within the heated fluid, all liability of the valve's clogging is prevented. Furthermore, by the above construction I have provided means whereby a valve located as above described may be readily operated from a point without the receptacle, and I have also provided means which effectively hold it in engagement with the valve seat.

Having thus described my invention, I claim:

1. The combination of a valve seat having an opening therethrough, a pivot stem at one side of said opening, a valve pivoted on said stem, a spring surrounding said stem and pressing the valve against its seat, a supporting projection engaging the valve in the inner face thereof and forming a fulcrum support to assist the spring in seating

said valve, said stem and spring being located between said projection and the opening in the valve seat.

2. The combination with a valve-seat plate having an opening therein, of a pivot stem secured to said plate at one side of the opening thereof, a valve pivoted on said stem, a spring surrounding said stem and pressing the valve against the plate, a projection on the plate forming a fulcrum support for the valve to assist the spring in pressing the valve against said plate when said valve is moved to close said opening, and a stop carried by the plate to limit the closing movement of said valve.

3. The combination with a valve seat plate having an opening therein, of a pivot stem secured to said plate at one side of said opening, a valve pivoted on said stem, a spring surrounding the stem, a projection

on the plate forming a fulcrum support for the valve, said pivot stem being located between the said fulcrum support and the opening in the valve seat plate, said valve on its inner face being free from contact with said plate between said fulcrum support and the seat around the opening in the plate for the valve, whereby said spring bearing against the valve seat plate at the opening therein, and a stop carried by the plate for limiting the closing movement of the valve.

In testimony whereof, I have hereunto signed my name at Buffalo, New York, this 7th day of April, 1913.

ALLAN J. AITKEN.
